Primary Examiner — Karen S Acker(74) *Attorney, Agent, or Firm* — Seed IP Law Group LLP(57) **CLAIM**

The ornamental design for a locking device, as shown and described.

DESCRIPTION

Locking device

4.1 : Front

4.2 : Back

4.3 : Left

4.4 : Right

4.5 : Bottom

4.6 : Top

4.7 : Perspective

1 Claim, 7 Drawing Sheets(56)
